Patented Jan. 29, 1918.

UNITED STATES PATENT OFFICE.

HARRY H. DARST, OF DAYTON, OHIO.

PAPER-FILE.

1,254,991.

Specification of Letters Patent. Patented Jan. 29, 1918.

Application filed November 27, 1916. Serial No. 133,720.

To all whom it may concern:

Be it known that I, HARRY H. DARST, citizen of the United States, residing at Dayton, in the county of Montgomery and 5 State of Ohio, have invented certain new and useful Improvements in Paper-Files, of which the following is a specification.

My invention relates to filing devices and more particularly to a file box or drawer 10 adapted for filing loose sheets or papers such as bills, statements, report sheets, etc.

The object of the invention is to simplify the structure as well as the means and mode of operation of such devices whereby they 15 will not only be cheapened in construction but will be more efficient in use, afford ready access to the contents for convenient examination, removal or replacement of any paper or sheet without disarrangement of 20 the order of the other contents of the file, convenient in arrangement, and unlikely to get out of repair.

A further object of the invention is to provide a filing device which may not only be 25 used singly or independent of other like devices, but which may also be employed as a drawer in a desk, filing cabinet or stack. In such event each drawer embodies an individual cover or closure which not only 30 renders the drawer or file device dust proof but it prevents the loss or displacement of papers over the back of the drawer or container within the cabinet or desk as frequently happens with the use of open 35 drawers or containers.

A further object of the invention is to provide a file device or container which when 40 opened will constitute two open sided trays connected one to the other, one of which 45 forms a receiving tray positioned at such angle that the papers or sheets contained therein will automatically register one with the other.

With the above primary and other incidental objects in view as will more fully appear in the specification the invention consists of the features of construction, the parts and combinations thereof and the mode of 50 operation or their equivalent as hereinafter described and set forth in the claims.

Referring to the drawing Figure 1 is a perspective view of a filing cabinet or stack embodying the filing drawers or containers forming the subject matter hereof. Fig. 2 55 is a perspective view of the filing drawer or container in closed condition. Fig. 3 is a

perspective view of same in its open condition.

Like parts are indicated by like characters of reference throughout the several 60 views.

In the drawings 1, is a cabinet or stack adapted to receive a series of file boxes or drawers 2. The boxes or drawers 2 may be supported within the cabinet or housing 65 upon fixed guides but are preferably supported upon the extension guides 3 as commonly employed in filing cabinets. The drawer or container 2 which forms the subject matter hereof, comprises two complementary units of similar shape, side and construction but are arranged in reversed 70 relation one to the other, and preferably though not necessarily hinged or otherwise flexibly connected. The units so connected 75 constitute a body portion and a cover therefor.

The body portion comprises a base or bottom 4 and a lateral or end wall 5 and a rear or back wall 6, thus forming a unit open on 80 its forward and righthand side. It is to be noted that the lateral or end wall 5 and the rear or back wall 6 extends the full height of the unit through their entire length while any semblance of a wall is entirely absent on the front and right hand 85 sides of the unit.

The cover unit is of similar size and proportion and construction in a similar manner except that the positions of the vertical 90 walls are reversed. The cover comprises a top or main section 7 carrying a front wall 8 and a lateral or end wall 9 at the right hand side of the cover section.

The several walls of the cover and body 95 units being thus oppositely disposed, the forward and lateral walls of the cover section fill the open forward and lateral sides of the body section when the device is closed, the sides of the respective units coact one 100 with the other to form a complete inclosure when the units are closed one upon the other.

For convenience of use the units are connected preferably though not necessarily by 105 hinges 10. It is obvious that in lieu of the hinges 10, hooks, links or other engaging means may be employed. When in use the file device is opened as shown in Fig. 3 with the free edge of the cover section resting 110 upon the table or support upon which the body also rests. The cover section is thus

inclined downwardly and rearwardly as indicated. The body section is open on its forward and right hand side rendering the contents of the body easily accessible. The 5 lowest sheet or paper may be reached as easily as the first or upmost sheet. As the sheets are removed from the body unit they are placed in reversed position in the top or cover unit. This unit being inclined 10 downwardly and rearwardly the sheets automatically collect in the corner or angle formed by the side and end walls 8 and 9 which serve as guides and limiting stops for the sheets causing them to register in 15 their piled or collected relation. The top or cover unit is open at the left side and forward side for easy access to the collected or piled sheets therein. To reassemble the sheets in their original order it is only necessary to close the device by turning the cover unit over the body unit or vice versa and the sheets will be found upon reopening the device reassembled in their original order in one pile or collection.

20 As shown in Fig. 1 the top may be merely raised without being inclined downwardly and rearwardly to permit access to the body portion of the device. In order that the drawers or filing devices may be more 25 readily removed and returned to the cabinet, drawer pulls 11 are provided. A locking device to interengage the cover and body portions in closed position may also be provided as indicated at 12.

30 It is to be noted that the device comprises two units which may or may not be flexibly connected according to the condition of use, which when closed form a complete box like container the sections or units of which each 35 comprise three complete walls or faces. Each unit comprises a bottom and two complete side walls of full extent, the side walls being oppositely arranged whereby when the units are turned one upon the other, the 40 side walls of each unit will fill those sides or open spaces from which the side walls are missing in the opposite or complementary unit.

45 From the above description it will be apparent that there is thus provided a device of the character described, possessing the particular features of advantage before enumerated as desirable but which obviously is susceptible of modification in its 50 form, proportion, detail construction or arrangement of parts, without departing from the principle involved or sacrificing any of its advantages.

55 While in order to comply with the statute, the invention has been described in language 60 more or less specific as to certain structural features, it is to be understood that the in-

vention is not limited to any specific details, but that the means and construction herein described comprise but one mode of putting 65 the invention into effect, and the invention is therefore claimed broadly in any of its possible forms or modifications within the scope of the appended claims.

Having thus described my invention I 70 claim:

1. A file box consisting of two units each comprising a bottom and two complete wall sections, the wall sections of the respective units being angularly arranged in relation with the other in complementary relation 75 with those of the opposing unit whereby when said units are turned one upon the other they will form a complete inclosure.

2. A file box consisting of two complementary units of similar size, shape and proportion arranged in reverse relation, each unit comprising a bottom section and two wall sections, each wall section arranged at a substantially right angle to the bottom and 80 to the other wall section, the said wall sections of each unit being adapted to fill the open sides of the complementary unit when closed one upon the other.

3. A file box comprising a top section, a 90 bottom section, and four vertical wall sections, two of the wall sections being attached to the top section and extending at right angles one to the other and two of the wall sections being attached to the bottom section and extending at right angles one to the other, said angularly arranged wall sections being attached to the top and bottom sections in complementary relation whereby 95 they coact to form a complete inclosure. 100

4. A file box comprising a cover unit and a body unit upon which the cover unit is supported in inclined position when the box is open, each unit being completely open on one side and one end, said units engaging 105 each other in reversed relation when closed whereby the open side and end of one unit will be closed by the closed side and end of the complementary unit.

5. A file box comprising two complementary units flexibly connected one to the other, each unit comprising three wall sections connected one to another and each extending in a plane at a substantially right angle to the planes of the other two sections. 110 115

In testimony whereof, I have hereunto set my hand this 18 day of November, A. D. 1916.

HARRY H. DARST.
